UNITED STATES PATENT OFFICE

123,249

DESIGN FOR A COMBINATION VANITY CASE AND APPOINTMENT INDICATOR

Christopher L. Migliaccio, Providence, R. I., assignor to Hingeo Vanities, Inc., Providence, R. I., a corporation of Rhode Island

Application June 20, 1940, Serial No. 93,116

Term of patent 3½ years

To all whom it may concern:

Be it known that I, Christopher L. Migliaccio, a citizen of the United States, residing at Providence, county of Providence, State of Rhode Island, have invented a new, original, and ornamental Design for a Combination Vanity Case and Appointment Indicator, of which the following is a specification, reference being had to the accompanying drawing, forming part thereof.

Fig. 1 is a face view of a combination vanity case and appointment indicator showing my new design, the vanity case being closed.

Fig. 2 is a perspective view thereof, the vanity case being opened, and

Fig. 3 is an edge view thereof.

I claim:

The ornamental design for a combination vanity case and appointment indicator, as shown.
